UNITED STATES PATENT OFFICE.

WILLIAM F. GAMMETER, OF CADIZ, OHIO.

STOCK-SHELL FOR WINDING FABRICS.

1,104,296.

Specification of Letters Patent. Patented July 21, 1914.

Application filed October 30, 1913. Serial No. 798,375.

To all whom it may concern:

Be it known that I, WILLIAM F. GAMMETER, citizen of the United States, residing at Cadiz, in the county of Harrison and 5 State of Ohio, have invented certain new and useful Improvements in Stock-Shells for Winding Fabrics, of which the following is a specification.

My invention relates to winding shells or 10 rolls such as are used in the manufacture of those fabrics which are worked hot and which are calendered, the improved winding shell devised by me being particularly applicable for the manufacture of sheet rubber 15 and being used in connection with the calenders or rolls which form the rubber compound into sheets. These sheets are run out upon the fabric and the fabric carrying this newly formed sheet is wound upon a roll to 20 facilitate handling and feeding the sheet rubber into the various machines through which it passes in the process of manufacture.

This invention is an improvement upon 25 the stock shell illustrated and described in by prior Patent, Number 1,003,593 of September 19, 1911, and the improvement particularly relates to the head of the shell.

One object of my invention is to so construct the head that the sheet metal shell 30 will not be broken or damaged by the insertion of the square iron mandrel into the shell. In the form of my invention illustrated in the patent before referred to, a 35 square tube is shown passing through the mandrel concentrically to its axis and disposed on the inside of the head. It has been found in practice that in using this form of shell, the workmen would insert the square 40 iron mandrel into the tube an inch or two and pry the loaded shell around breaking the tube down sufficiently to expose the tail piece of castings so that when the mandrel was being put clear through the shell, the 45 mandrel would knock the head out. It is to avoid this objection that I have devised the present form of head for the shell and the manner of connecting the central tube to this head.

50 A further object of the invention is to strengthen the tube and so construct it that it will distribute the strain along the entire length of the tube when the shell is in use.

My invention is illustrated in the accompanying drawings wherein:

Figure 1 is a perspective fragmentary

view of a shell constructed in accordance with my invention. Fig. 2 is a perspective view of one of the heads of the shell looking at the inside thereof. Fig. 3 is a longitudinal diametrical section of the shell and head. Fig. 4 is a reduced cross section on the line 4-4 of Fig. 3.

Corresponding and like parts are referred to in the following description and indicated in all the views of the accompanying drawings by the same reference characters.

Referring to these drawings, 2 designates an ordinary shaft or mandrel square in section at its middle portion, this shaft or mandrel being cylindrical at its ends. Shafts or mandrels of this character are usually used for the purpose of supporting and rotating winding rolls of this nature. In order not to obscure the drawing this shaft 75 or mandrel is illustrated in dotted lines in Fig. 1 only.

Mounted upon the shaft 2 is the stock shell. This stock shell consists of a cylinder of thin metal designated 3 and opposed 80 heads 4 supporting the ends of the cylinder. One of these heads 4 is illustrated in Fig. 2. Each head comprises a disk-like portion 5 having a circumferential outwardly extending flange 6. The face of this flange for a 85 portion of its width is cut away as at 7 so as to leave an outwardly projecting shoulder 8 at the extremity of the flange. This cut-away portion has approximately the thickness of the metal cylinder 3. The center of 90 each head 4 is formed with a square aperture 9 and the metal of the head around this square aperture is formed to provide the inwardly projecting walls 10 as illustrated clearly in Fig. 2. There are two of these 95 walls 10 diametrically opposite to each other, each of the walls being angular in form so as to extend along two sides of the square aperture. At the junction between the walls 10, the walls are separated from each other as at 100 11, the edges of the walls diverging slightly outward. The body of each head is formed with a plurality of ventilating perforations 12. The metal cylinder 3 is held to each of the heads by means of rivets 13 which are 105 countersunk in the metal of the cylinder so as not to interfere with the proper winding of the fabric thereon. The intermediate portion of the shell is reinforced by one or more rings 14 to which the shell may be riveted.

Mounted upon the flanges or walls 10 and extending from one head to the other and

forming a central guiding passage through which the mandrel 2 may be placed and guided in position, is the sheet metal casing or tube 15. This tube as illustrated in Figs. 1 and 4 is square in form and has the same cross sectional area as the area of the opening 9. The tube 15 is formed of two pieces of sheet metal each of a length adapted to extend from one head to the other, each piece being angularly bent longitudinally.

10 The margins 17 of each of the sheet metal sections 16 is outwardly bent and the marginal edges of one section 16 lie against and confront the marginal edges of the other section 16. These sections 16 are held to each other by means of rivets or in any other suitable manner.

15 The completed tube 15 is adapted to be inserted at its ends within the walls 10 with the projecting margins 17 projecting through the clefts or spaces 11 as illustrated clearly in Fig. 4, the ends of the tube abutting solidly against the margin of the opening 9, the flanges 10 being spaced slightly from the wall of the opening to provide this margin or shoulder. In my former patent this tube was formed of one piece of sheet metal, square in cross section, and was adapted to fit over walls corresponding to the walls 10.

20 There was no way of fastening this tube in place and, furthermore, inasmuch as the tube passed over the walls corresponding to the walls 10, the ends of the walls formed ledges which would be struck by the mandrel when inserting it and this would tend to damage the shell. By my present invention the tube 15 extends into and forms a lining for the walls 10 of each head and the tube therefore extends from end to end of the stock shell so that there is no projection on the inside of the tube against which the mandrel will strike. Furthermore, by forming the tube with the flanges 17 and inserting these flanges in the slots or clefts 11, the tube is 25 very rigidly connected with the head so that the head and tube will rotate together and rotational strain will be transmitted from one head to the opposite head, not only by means of the shell but by means of the central tube.

30 With this new construction the ends of the tube enter the heads of the shell and as a consequence the mandrel when inserted and pried around can not spread the tube. Furthermore, this tube forms a passage for the mandrel of uniform diameter throughout its length so that when inserting the mandrel it is impossible to knock the heads out or weaken the heads. Furthermore, inasmuch as the flanges 17 of the tube are securely held in the slots of the tail piece, any strain put on one head is transmitted to the other head most effectually.

35 While it forms no part of my present invention and is clearly described and claimed

in my original patent before referred to, it may be explained that the cylinder 3 does not extend entirely around the shell but that the edges of the cylinder 3 are spaced from each other as at 18. The margins of the sheet are, however, connected by a bridging plate 19 which is riveted or otherwise attached at its edges to the margins of the sheet metal 3.

40 The apron 20 is formed of canvas, duck or other suitable fabric and is detachably connected to the shell. To this end, the apron at one end is provided with a longitudinally extending pocket or hem into which a metallic strip 21 is inserted. In order to attach the apron to the roll, it is only necessary to insert the metal strip 21 into the hem at the edge of the apron and insert the edge of the apron and strip into the slot 18. This metallic strip is, of course, wider than the slot 18 so that after it is inserted from the end of the shell it can not be removed except by withdrawing it longitudinally. The object of this apron is to clamp or bind the sheet of compound and fabric upon the roll or shell so that it may be easily wound thereon. In starting to wind the sheet of fabric and the new sheet of rubber upon the roll, the apron is raised and the fabric carrying the rubber is started under it. A complete rotation of the shell causes the fabric to close down upon the apron and the apron being anchored to the shell, binds the end of the fabric and the rubber closely to the shell.

45 In use, the roll is placed upon the mandrel or shaft and the shaft connected to any means for rotating it. The roll is rotated and the stock is wrapped thereon, one convolution upon the other until the desired amount of stock has been received upon the roll. After the proper amount of stock has been rolled upon a given roll, the shaft may be removed and placed in any desired position. The object of providing perforations in the heads 4 is to permit the heat conducted to the shell to be rapidly dissipated. It will be seen that this absorption of the heat of the stock by the roll is aided by the fact that the cylinder 3 is of thin sheet metal so that the heat is readily communicated to the air inside of the roll and this air will be constantly changed by means of the ventilating openings in the heads.

50 The object of forming the shell of metal rather than wood, as was the practice prior to my patent before referred to, is to not only dissipate the heat but provide a roll which will carry off the frictional electricity generated by the friction of milling or rolling the rubber into sheets. As this is fully described in my prior patent, there is no need of a more extended reference here.

55 What I claim is:

60 1. A stock roll for winding sheets of hot

- material including a hollow cylindrical shell of relatively thin metal, end pieces or heads carried within the ends of the shell, each head comprising a body portion having a peripheral flange supporting the shell and having a central, many sided aperture, said aperture having inwardly extending walls and said walls being longitudinally slotted, and a central tube extending through the cylinder and attached to said end pieces and having flanges extending radially through the slots of the head.
2. A stock roll for winding sheets of hot material including a hollow cylindrical shell of relatively thin metal, metallic end pieces or heads within the ends of the shell, each comprising a body portion having a peripheral flange engaging the shell, the center of each head being formed with a many sided aperture, the head being formed with walls extending inward and defining said aperture, said wall being formed with longitudinally extending slots, and a central tube extending through the cylinder from end to end, said tube being many sided and being formed in sections, the margins of the sections being outwardly flanged, said flanges extending through the slots of the wall of each head and the tube being disposed upon the inner face of said wall.
3. A stock roll for winding sheets of hot material including a hollow cylindrical shell of relatively thin sheet metal having a smooth exterior face from end to end, metallic end pieces or heads supporting the ends of the shell, each of said end pieces consisting of a disk-like body portion having a peripheral flange formed with a marginal shoulder, said shoulder engaging the corresponding end of the shell, the center of the body being formed with a many sided mandrel aperture, each head having an inwardly extending wall surrounding said aperture, the wall being longitudinally slotted at a plurality of points, and a central mandrel receiving tube extending through the cylinder from end to end and attached to said heads, said tube being formed of angular sections having marginal flanges whereby the sections may be attached to each other, the ends of said flanges extending through the slots in the wall of each head and the ends of said tube being disposed on the inner face of the wall.
4. A stock roll for winding sheets of hot material including a hollow cylindrical shell, end pieces or heads carried within the ends of the shell, each head being formed with a central opening having inwardly extending, longitudinally slotted walls, and a central tube extending through the cylinder and engaging the heads, said tube having radially disposed flanges engaging with the slots of said walls.
5. A stock roll for winding sheets of hot material including a hollow cylindrical shell, end pieces or heads carried within the ends of the shell, each head being formed with a central opening having walls projecting from the head parallel to the shell, and a central tube extending through the cylinder and engaging the heads, said tube and wall having one, a radially disposed projecting portion, and the other a radially disposed slot within which the projecting portion is received to thereby connect the tube to the head for rotary movement therewith.
- In testimony whereof I affix my signature in presence of two witnesses.
